FUSE FOR PROJECTILES

Léon Emile Remondy, Paris, France

Application September 27, 1934, Serial No. 745,807
In France July 31, 1934

1. Claim. (Cl. 102—39)

In Letters Patent No. 1,854,669, I have described and shown a fuse for artillery and aircraft projectiles comprising a movable carriage the casing of which contains the entire percussion mechanism (striker and percussion cap), wherein the striker (front element) is solid with the carriage, while the percussion cap (back element) is slidably mounted within the casing so that there may be relative movement between said cap and the striker. This construction also includes a winged washer which forms an abutment in the inoperative position for the percussion cap and prevents any forward movement of the latter, the wings of said washer passing through openings in the side of said carriage so that the latter is free to move rearwardly upon impact. This prior patent relates to an improved fuse of this known type, the improvement comprising means for constructing the movable carriage with an extremely small weight.

The novel means disclosed in said Patent No. 1,854,669 consists primarily of a support forming an auxiliary resistance to the recoil of the percussion cap, the said percussion cap being obliged to force the said support backwardly, driving the base of the movable carriage, after having ruptured the connection which exists between the said support and the fuse body and is provided, for example, by a system of frangible or shearable pins.

The present invention relates to various practical forms of construction of the resistance of the auxiliary support provided for the percussion cap of the movable carriage.

In the Letters Patent No. 1,854,669, two forms of construction were described in detail in which the auxiliary rear support of the percussion cap was constituted by a thimble or cup having a perforated bottom and fixed to the fuse body by a system of frangible pins, the cup being disposed immediately below the bottom of the casing of the carriage or in the interior of the said casing and between the bottom of the latter and the bottom of the percussion cap.

The modified and improved forms of construction of the basic invention according to the Patent No. 1,854,669 which form the subject-matter of the present invention are shown in the accompanying drawing. These forms of construction differ from those described in the Patent No. 1,854,669 in the manner of constituting the auxiliary support and the member or members which, in the inoperative position, secure it to the fuse body. The general principle of the invention remains the same, that is to say, the fuse always

comprises an auxiliary rear support, resting on which is the carriage or the percussion cap, prevented from any forward escape by a member such as a resilient winged washer, and the percussion cap always encounters on the departure of the projectile, as resistance against any premature inward movement, not only the bottom of the casing of the carriage, but also the said auxiliary support and the means for holding it to the fuse body. Exactly as in the forms of construction described in the Patent 1,854,669, it is no longer necessary in the present invention to make the carriage casing of a strength such that the casing is capable of retaining by itself the percussion cap, a fact which makes possible of attainment a considerable lightening of the carriage structure.

Several embodiments of the invention are shown in the accompanying drawing wherein:

Figure 1 is a sectional elevation of the upper part of a fuse body illustrating one form of the invention;

Figure 2 is a perspective view of the auxiliary supporting element shown in Figure 1;

Figure 3 is a view similar to Figure 1 of a modification of the invention;

Figure 4 is a plan view of the auxiliary support of Figure 3; and

Figures 5 and 6 are views similar to Figure 1 of two additional forms of the invention.

In the embodiment shown in Figure 1, *a* denotes the principal element of the fuse body in which is mounted the movable carriage, constituted by a casing *b* expanded at its forward end and set on the expanded head *c* of the striker *c*—*c*¹. The longitudinal walls of the said casing are pierced by openings *b*¹. The percussion cap *f* which is contained in the casing *b* bears at its rear end on the bottom of the casing and at its front edge against the winged washer *h*, being thus fixed between its two supports in the inoperative position.

In the example shown, the auxiliary rear support for the percussion cap is constituted by an inverted cup *e* perforated in the central portion of base at *e*¹ for flame transmission, as shown in the detailed perspective view of Figure 2. The members for fixing the cup to the fuse body are integral with the body of the cup and may be constituted by a certain number of lugs or wings *g*, clamped between the element *a* of the fuse body and an element *a*² which is housed within the detachable fuse cap *a*¹, said element *a*² having a shoulder *a*³ which engages the upper face of each wing *g* and clamps the

latter against the front edge of the element a . Of course, the element a^2 of the fuse body will at the same time serve for fixing the winged washer h^1 in position by clamping engagement 5 between its upper surface and a shoulder formed on fuse cap a^1 . The winged washer h^1 may be constituted exactly as is indicated in the Patent 1,854,669.

With a view to increasing the sensitivity of 10 the fuse, the line of connection g^1 between the lugs g and the body e of the cup $e—e^1$ may be weakened so that, immediately upon impact, body e is sheared from lugs g and permits the carriage b to move rearwardly. This movement 15 of the carriage brings striker c into contact with percussion cap f , which by its inertia tends to remain in its forward position abutting washer h^1 .

It is easy to see that this form of construction, 20 when compared with those which have been described and shown by way of example in the Patent 1,854,669 affords the additional advantage of an easier assembly in view of the fact that any drilling of gauged holes of very small diameter, and the operation of the engagement and retention of frangible or shearable pins in the 25 said holes are avoided.

In the embodiment shown in Figure 3, the auxiliary support for the percussion cap, disposed 30 as in the example of Figures 1 and 2 on the exterior of the casing of the movable carriage, instead of being integral with its fixing member is independent thereof. In this construction, 35 as is shown clearly by Figure 3 and the corresponding plan of Figure 4, the perforated cup e rests by its edge on a perforated washer $g—g^1$ fixed at its periphery between the two elements a and a^2 of the fuse body.

As shown in Figure 4, the washer g may be 40 provided with a plurality of arcuate slots g^2 which are so located as to line up with the lower edge of the cup e , the latter only resting on two or more solid parts g^3 of slight width separating slots g^2 . This construction will considerably facilitate 45 the shearing upon impact of the central cup retaining portion of washer g from its peripheral portion which is clamped between elements a and a^2 of the fuse body.

Figure 5 shows a form of construction in which 50 the supporting cup e is inverted from the position shown in Figure 1 so as to constitute a kind of socket for the carriage. The fixing portion of the cup, integral with the said cup, may be constituted either by a continuous flange 55 or by lugs g analogous to those of Figure 2, said flange or lugs being clamped between elements a and a^1 of the fuse body just beneath winged washer h^1 .

It will be understood that in this embodiment 60 also lines of lesser resistance may be provided between the socket body and the inner edges of the fixing lugs, or between the bottom of the cup and the body thereof.

In all these embodiments, the depth or height 65 of the body of the cup may be varied as desired.

It is also possible to replace the cup by a sim-

ple washer which may or may not be slightly dished whether or not the body of the cup serves for shearing the retaining member by pressure or serves as stripping member.

Figure 6 shows a constructional embodiment 5 in which the auxiliary support is formed under the movable carriage simply by a washer analogous to that shown in Figure 4. In this construction, the washer is retained by circumferentially spaced teeth a^3 projecting upwardly from 10 the element a of the fuse body and passing through the apertures cut in said washer, the said teeth at the same time forming guides for 15 the lower end of the casing of the movable carriage.

Of course, the fuses above described may comprise, associated with the improved percussion system, the various accessory devices described and shown in my prior patent specifications, such as gas-tight caps or joints, firing safety devices having segments retracted by the centrifugal force, and devices for absorbing any shocks on the departure of the shot, such as washers of felt, cloth or the like placed under the head (Figure 6) or under the lower end of the movable carriage.

Although the auxiliary supporting member with its fixing means is preferably made of a light alloy, it may of course be made of any other suitable material capable of being moulded, stamped or cut and adapted for easy manufacture. It will not be indispensable for the material employed to be homogeneous. The cup or washer forming the auxiliary supporting member may be constituted of superimposed sheets, so as to provide an upper layer of a plasticity differing from that of the lower layer or layers. Various other changes, which will now suggest themselves to those skilled in the art, may be made in form, details of construction and arrangement of the 40 parts without departing from the spirit of the present invention. Reference is therefore to be had to the appended claim for a definition of the limits of the invention.

What is claimed is:—

In a projectile fuse of the type having a carriage movably mounted within the fuse body and relatively movable striker and percussion cap elements carried thereby, a supporting member for preventing premature movement of said carriage and elements to firing position having a central portion in the form of a cup with an apertured end wall upon which the carriage is adapted to rest and side walls perpendicular to said end wall, and an outer portion consisting of a plurality of spaced lugs integral with and extending outwardly from said side walls for fixed clamping engagement between separable elements of the fuse body, the junction between 60 said central portion and said lugs offering less resistance to forces acting parallel to the axis of the fuse than any other part of said supporting member, whereby shearing of the central portion from the lugs upon impact of the 65 projectile is insured.

LÉON EMILE REMONDY.
